TOOTH FOR AN EARTHWORKING TOOL

Maxwell C. Orendorff, Fresno, Calif., assignor to
Max C. Orendorff Co., a corporation of California

Filed Mar. 21, 1966, Ser. No. 1,557

Term of patent 14 years

(Cl. D39—1)

FIG. 1 is a front elevation of a tooth for an earthworking tool, showing my new design.

FIG. 2 is a side elevation thereof, the opposite side of the tooth being identical to the side shown.

FIG. 3 is a rear elevation thereof.

FIG. 4 is an end elevation thereof, the opposite end of the tooth being identical to the end shown.

FIG. 5 is a perspective view thereof.

I claim:

The ornamental design for a tooth for an earthworking tool, as shown and described.
